UNITED STATES PATENT OFFICE.

JAMES A. DRAGOON AND DICKMAN D. DRAGOON, OF CONNERSVILLE, INDIANA.

VACCINATING-TABLE.

1,218,381.

Specification of Letters Patent.

Patented Mar. 6, 1917.

Application filed April 4, 1916. Serial No. 88,928.

To all whom it may concern:

Be it known that we, JAMES A. DRAGOON and DICKMAN D. DRAGOON, citizens of the United States, residing at Connersville, in 5 the county of Fayette and State of Indiana, have invented certain new and useful Improvements in Vaccinating-Tables, of which the following is a specification.

This invention has relation to veterinary

10 appliances with special reference to vaccinating tables and the nature and objects thereof will be apparent to those skilled in the art, in the light of the following explanation of the accompanying drawings, 15 illustrating what we now believe to be the preferred embodiment, or mechanical expression of our invention, from among other forms within the spirit of the invention and the scope of the appended claims.

20 However, an object of the invention is to provide a vaccinating table upon which to support, and securely hold hogs, pigs, and other small animals for the performance thereupon of operations incidental to the 25 practice of veterinary surgery.

Another object of the invention is to provide a table of the character described which is portable, and which may be disassembled and its parts conveniently packed for trans- 30 portation.

In addition to the foregoing our invention comprehends improvements in the details of construction and arrangement of parts to be hereinafter described, and particularly 35 pointed out in the appended claims.

In the accompanying drawings in which similar and corresponding parts, are designated by the characters of reference throughout the several views in which they appear,

40 Figure 1, is a view in side elevation of a vaccinating table constructed after the manner of my invention,

Fig. 2, is a plan view thereof,

Fig. 3, is a transverse section on the line 45 3—3 of Fig. 1, and

Fig. 4, is a similar section on the line 4—4 of Fig. 1.

This invention finds its greatest degree of employment in the vaccination of hogs. In 50 hog raising countries, especially the middle Western States, the disease known as hog cholera is widely prevalent, and occasions at times losses of considerable magnitude to breeders of these animals. It has now be-

come the practice to vaccinate, or inoculate 55 the hogs with anti-toxin which mitigates the contagious properties of the disease. It is evident that if a herd of swine comprising great numbers is to be inoculated some means must be provided for holding them conveniently, without discomfort to the operator, and whereby they may be quickly placed into position and as quickly released.

We have devised an arrangement for carrying out the operations mentioned above, 65 and which comprises a supporting element formed of a pair of longitudinal members 1 of galvanized iron or the like, and disposed with their lower longitudinal edges in proximity but slightly spaced, and their sides 70 diverging upwardly to form a V-shaped trough. Hinges 2 are provided for connecting together the lower edges of the members 1 whereby said members may be folded together for packing.

75 One extremity of the trough element is supported upon a member formed of a transversely extending strap iron having a V-shaped bent portion 3 the sides 4 of which are adapted to support the members 1 in 80 V-shaped relation, said strap iron being continued at the upper edges of the members 1 in a horizontal direction to form portions 5, and then downwardly as at 6 to form supporting legs. The opposite terminal of 85 the trough shaped member is preferably disposed at a higher elevation so as to incline said trough shaped member and to that end is supported upon a member formed of strap iron, and having a V-shaped bend at 7 and 90 upwardly diverging portions 8 upon which are supported the members 1 in V-shaped relation. The strap iron member just mentioned is continued downwardly and longitudinally for a distance beyond the terminal 95 of the trough shaped member to form supporting legs 9.

The members 1 and the portions 4 and 8 of the strap iron support are provided with registerable openings in which are seated 100 bolts 10 having flattened rounded heads 11 disposed on the adjacent faces of the members 1 and thumb nuts 12 on the shanks of the bolts for securely clamping the members 1 and the supports together. At the lower 105 end of the trough shaped member we provide a transversely extending rod 13 having down turned threaded terminals 14 which

are seated in apertures in the horizontal portions 5 of the trough support. Thumb nuts 15 are applied to the threaded terminals for securing the same in any desired 5 vertical adjustment in conjunction with nuts 16.

In use the hog is laid upon its back in the V-shaped trough with its head directed toward the lower portion of the trough, and is 10 slid downward until its nose and head is caught beneath the transverse bar 13. The assistant then catches hold of the animal's hind legs whereupon the animal is rendered absolutely helpless and is unable to free its 15 self, or change its position. Heretofore the method of securing the animal during operation was to either suspend it from its hind legs or hold it to the ground upon its side; in either of these positions the animal 20 exerts considerable effort in attempting to release itself. In our experience in the use of this invention we find that the animal remains quiet while on its back, and one assistant is enabled to hold a two hundred 25 pound hog where heretofore three men were necessary besides the operator.

While our invention is intended primarily for use in vaccinating hogs, it nevertheless finds ready employment as a general operating table for the performance of various 30 surgical operations upon hogs, pigs, and other small animals. Various ways of constructing our invention will occur to those, skilled in the art to which it appertains, and 35 we therefore reserve the right and privilege of changing the form of the details and otherwise altering the arrangement of parts without departing from the spirit of the invention or the scope of the appended claims.

40 Having thus described our invention what

we claim as new and desire to secure by Letters Patent is:—

1. A vaccinating table comprising a trough shaped member, means for supporting the same at an inclination, a transversely 45 extending support at the lower end of the member having an aperture at either end adjacent the upper longitudinal edges of the member, a transversely extending rod above the trough member, adjacent the support to 50 retain the head of an animal under said rod and having down-turned threaded ends which enter the openings, and nuts applied to the threaded ends above and below the support to retain the rod in any vertically 55 adjusted position.

2. A vaccinating table comprising longitudinal members hingedly connected at one of the longitudinal edges, supports formed of strap iron and provided with V-shaped 60 bends for supporting the longitudinal members in angular relation, and in an inclined position relative to the ground, the longitudinal members and the V-shaped bends of the supports having registerable openings, 65 removable fastenings extending through the openings for securing together the members and the supports, a rod, having parallel threaded terminals for engagement in the support at the lower end of the members, and nuts engaging the threaded terminals and the supports for maintaining the rod in 70 adjusted position.

In testimony whereof we affix our signatures in presence of two witnesses.

JAMES A. DRAGOON.
DICKMAN D. DRAGOON.
